DESIGN FOR A SHOE RACK

Stanley J. Brown, Elm Grove, Wis., assignor to Met-L-Top Tables Inc., Milwaukee, Wis., a corporation of Illinois

Application March 13, 1944, Serial No. 112,880

Term of patent 3½ years

(Cl. D80—9)

To all whom it may concern:

Be it known that I, Stanley J. Brown, a citizen of the United States, residing at Elm Grove, in the county of Waukesha and State of Wisconsin, have invented a new, original, and ornamental Design for a Shoe Rack, of which the following is a specification, reference being had to the accompanying drawing, forming a part thereof, and in which:

Fig. 1 is a perspective view of a shoe rack, showing my design; and

Fig. 2 is a side elevational view of my design on a reduced scale.

I claim:

The ornamental design for a shoe rack, as shown.

STANLEY J. BROWN.
